UNITED STATES PATENT OFFICE

2,332,056

ENGINE

Joseph M. Caldwell, Burbank, Calif.

Application March 16, 1942, Serial No. 434,866

21 Claims. (Cl. 123—50)

My invention relates to internal combustion engines, and more particularly to a four-cycle, opposed piston, reciprocating sleeve type engine.

An object of my invention is to provide a simplified and more efficient means of converting reciprocatory motion imparted by an explosive mixture into a rotary motion in a condition to do any work desired.

I am aware that there are a good many devices known to the art for translating an explosive reciprocatory motion into a working rotary motion. However, each of the particular types known to the art embodies serious disadvantages which are eliminated in my invention.

The internal combustion engines known to the art fall into three general classes, viz.: type of reciprocating member, valve means, and means for translating the reciprocatory motion into rotary motion.

The most common type of reciprocating member employed is a piston. Those engines employing reciprocating pistons and operating as four-cycle engines employ auxiliary valves. These valves may be either poppet or sleeve types. In either event, a complex system of timing gears, cams and push rods must be employed for the proper functioning of the motor. Such extra moving parts are a constant source of trouble and repair and an added burden and expense of manufacture. An object of my invention is to provide an internal combustion engine operating on a four-cycle principle employing a minimum of moving parts, and eliminating all auxiliary means for timing the valve openings, rendering it comparatively free from costly repairs and complexities of manufacture.

I am aware that there are internal combustion engines known to the art which have eliminated auxiliary valve mechanisms. However, so far as I am aware, there is no such engine which operates on the four-cycle principle, but are, so far as is known to me, two-cycle engines. The two-cycle engine embodies several disadvantages, the most serious of which is the fact that a substantial portion of the power stroke is lost in exhausting, scavenging and refilling the combustion chamber. A further object of my invention is to provide an internal combustion engine embodying the same simplicity of construction of a two-cycle engine and the advantages in operating efficiency of a four-cycle engine.

In the drawings:

Figure 1 is a side elevation in cross-section of an engine embodying my invention.

Figure 2 is cross-section taken on line 2—2 in Figure 1 showing details of a cam follower.

Figure 3 is a cross-section taken on line 3—3 in Figure 1 showing details of valve parts and spark plug cluster.

Figure 4 is a schematic view of the cam.

Figure 5 is a view similar to Figure 3 showing the reciprocating sleeve at top center beginning the intake stroke.

Figure 6 is a similar view showing the sleeve at bottom center beginning the compression stroke.

Figure 7 is a similar view showing the sleeve at top center beginning the power stroke.

Figure 8 is a similar view showing the sleeve at bottom center beginning the exhaust stroke.

Figure 9 is a partial section similar to Figure 1 showing the sleeve at top center beginning the intake stroke.

Figure 10 is a similar view showing the sleeve at bottom center beginning the compression stroke.

Figure 11 is a similar view showing the sleeve at top center beginning the power stroke.

Figure 12 is a similar view showing the sleeve at bottom center beginning the exhaust stroke.

The standard means employed to translate reciprocatory motion into rotary motion comprises a crank shaft or cam throw and a rod connecting the reciprocating member to the crank or cam shaft. In such a construction the reciprocating member tends to wear the cylinder walls into an elliptical shape necessitating costly repairs and resulting in loss of operating efficiency.

I am aware that there are engines known to the art which eliminate such crank shafts and connecting rods by employing a cam race and cam follower to translate reciprocatory motion into rotary motion. However, so far as I am aware no such motor operates on a four-cycle principle.

A further object of my invention is to provide an internal combustion engine which combines the advantages contained in valveless, four-cycle, cam-race engines and at the same time eliminating the disadvantages heretofore discussed.

A further object of my invention is to provide an internal combustion engine, which may be manufactured in separate units of two opposed combustion chambers. Such a construction makes for simplicity of manufacture and allows the interchange of units in event repairs are necessary.

A further object of my invention is to provide a motor which may be manufactured in units

and assembled in any number or design without having to redesign any part of the assembly.

Further objects and advantages of my invention will be apparent from a detailed description of it.

The embodiment of my invention illustrated comprises a housing 10 formed with a longitudinal cylindrical bore 11, a reciprocating and rotating member 12 disposed within the bore 11, a cam follower 13 mounted on one end of the reciprocating member 12, a pair of stationary cams 14 and 15 disposed at one end of the housing 10 and defining a simple harmonic cam race 16, a stationary compression head 17 disposed within one end of the reciprocating member 12, a rotating compression head 18 disposed within the other end of the reciprocating member 12 and slidably connected to the cam follower 13, and means for employing the rotary motion of the head 18, illustrated here for the sake of convenience as a gear 19.

The housing 10 comprises a cylinder block 20 and a cylinder head 21 mounted on one end of the block 20. Openings 22 and 23 are cut through the side of the block 20 to provide exhaust and intake ports respectively. Exhaust port 22 and intake port 23 are illustrated as rectangular openings, and are shown as extending substantially the full length of the stroke of the reciprocating member 12. However, these ports may be of other shapes, such for example, as following the simple harmonic curves of the cam race 16, without departing from the spirit of my invention. The position and length of the exhaust port 22 and intake port 23 will be varied by the valve timing desired in the operation of the motor, as hereinafter explained. The cylinder block 20 is provided with cooling fins 24. It is obvious that a water jacket could be provided in place of the fins 24 to cool the motor without departing from the spirit of my invention, the method of cooling being a matter of choice and design.

The reciprocating member 12 comprises a cylindrical sleeve 25 and a diaphragm 26 dividing the sleeve 25 into combustion chambers 27 and 28. Openings 29 and 30 are cut through the wall of the sleeve 25 in chambers 27 and 28 respectively adjacent the diaphragm 26. During the operating of the motor, the reciprocating member 12 rotates as it reciprocates causing the openings 29 and 30 to register with ports 22 and 23, thereby acting as valves for the exhaust port 22 and intake port 23. To one end of the sleeve 25; i. e., the upper end in Figure 1, is securely fastened by any suitable means, the cam follower 13.

The stationary combustion head 17 is disposed within one end of the sleeve 25. A plurality of compression rings 31 are disposed in grooves about the periphery of the head 17 to aid in sealing combustion chamber 27. The head 17 is securely held in place by means of a stud bolt 32 which buts against cylinder head 21 by shoulder 33 resting upon the cylinder head 21, and a reduced portion of which stud bolt passes through a hole 34 in the cylinder head 21. The stud bolt 32 is fastened to the cylinder head 21 by means of a nut 35, with a washer 36 preferably interposed.

The head 17 is cooled by means of an oil spray 37, which spray 37 is supplied from any suitable source by means of a tube 38 and a hole 39 drilled through the stud bolt 32, which hole communicates with orifices 39a opening against an inverted frustoconical baffle 39b.

The reciprocating motion of the sleeve 25 is

converted into rotary motion by means of the cam follower 13 co-operating with the cam race 16. The cam follower 13 is slidably connected to a rotating member 40. This rotating member 40 comprises a yoke 41 rotatably mounted in a frame 42 by means of any suitable bearing 43 designed to absorb a thrust. The yoke 41 comprises a head 41a, and projecting studs 41b. Cylindrical sleeves 44 enclose the studs of yoke 41 and are securely fastened thereto by means of pins 45. A yoke 46 is threaded into the combustion head 18 by a threaded boss 47. This yoke 46 comprises a head 46a, and projecting studs 46b corresponding to the studs 41b. The studs of said yoke 46 are enclosed by the opposite end of sleeves 44, and are held by means of pins 48. Cores 49 fill the space within the sleeves 44 between the studs 41b and 46b for the purpose of increasing strength and rigidity of the sleeve connections between the upper and lower yokes 41 and 46.

The gear 19, or other suitable means for employing the rotary motion of the assembly described as rotary member 40 is mounted on a stub shaft 19a of the yoke 41 seating against a shoulder 50 on the yoke being secured by a nut 51. The gear should be either keyed to the stub shaft as at 52, or otherwise made rigid with the shaft.

The gear 19 meshes with a gear 53. Gear 53 is sweated or keyed to a jack shaft 54, which is mounted on the frame 42 by any suitable bearings 55.

It will readily be seen that any number of the above described combustion units may be employed in various combinations by means of a series of gears.

The cam follower 13 comprises a circular hollow body 56 (Fig. 2) with cam journals 57 diametrically projecting from the periphery of the body 56. A pair of diametrically opposed brackets 58 extend inwardly from the inner surface of the body 56. Holes 59 are formed in the brackets 58 enclosing sleeves 44 of the rotating member 40 and providing a slide bearing relationship between the cam follower 13 and the rotating member 40. It is obvious that any type of spline fitting may be employed for mounting the cam follower 13 on the rotating member 40 in place of the parallel sleeves 44.

Further incidental details of the engine and further particulars of the relationship of certain parts will be described in connection with the operation of the engine.

The operation of my engine can best be understood by reference to Figures 4 to 12 inclusive. The reciprocating sleeve 25 and diaphragm 26 in cooperation with compression heads 17 and 18 form two opposed combustion chambers 27 and 28. Each of said combustion chambers is provided with spark plug cluster 60 and 60a located adjacent the cylinder heads 17 and 18. One spark plug per combustion chamber will suffice, but two assure better operation.

I shall describe the four stroke operation of the combustion chamber 28 only, it being understood that the operation of combustion chamber 27 is substantially identical. In describing the operation of the engine I shall refer to the valve timing which I prefer, but it is understood that other valve timing may be employed for a specific function desired.

Figures 5 and 9 show the reciprocating sleeve 25 at top center at the beginning of the intake stroke. As hereinafter used the terms "top center" and "bottom center" refer to the top and

bottom of the simple harmonic curve defined by the cams 14 and 15 and the cam race 16 as illustrated in Figure 4. It will be noted from Figure 5 that the opening 30 in the sleeve 25 overlaps the exhaust port 22 and intake port 23, 5° of each port. I prefer to begin opening the intake port 23 at least 5° before top center *a* (Figure 4), and closing the exhaust port 22, 5° past top center *a*, the reason for this being that the natural inertia of the gas in the exhaust stroke will continue to carry the combusted gases from the chamber and result in a more efficient scavenging of the combustion chamber.

Figures 6 and 10 show the sleeve at bottom center at the end of the intake stroke and the beginning of the compression stroke with the cam follower 13 at position *b* (Figure 4). It will be noted that the opening 30 in sleeve 25 is still in cooperation with intake port 23 by 25°. I prefer this valve timing for the reason that natural inertia of the gas coming into the combustion chamber will continue to fill the chamber even though the sleeve 25 is starting on the compression stroke.

As the sleeve 25 travels upward on the compression stroke, the cam follower 13 moves in the cam race from *b* (Figure 4) toward *c*, thereby turning the sleeve 25 to a position where it registers with the spark plug cluster 60. This position is intermediate of the positions illustrated in Figures 6 and 7, and 10 and 11. The spark plug cluster 60 is so electrically timed that it will fire approximately 25° before top center *c*, the reason for this being that since the spark plugs are on the side of the combustion chamber the flame front in the combusted gas will not be fully distributed throughout the combustion chamber until the sleeve has reached the top center *c* at which time full effect of the explosion will be felt and a more efficient operation of the motor will result.

Figures 7 and 11 show the sleeve 25 at top center *c* just beginning the power stroke. As the power stroke expands, cam follower 13 follows the cam race 16 to bottom center *d*.

Figures 8 and 12 show the sleeve 25 at bottom center *d* at the beginning of the exhaust stroke. It will be noted in Figure 8 that the opening 30 in sleeve 25 is in cooperation with exhaust port 22 by 25°. I have found that this valve timing results in a more efficient scavenging of the combustion chamber without any substantial loss of power. As the sleeve 25 moves up on the exhaust stroke, cam follower 13 follows cam race 16 from bottom center *d* to top center *a* where the motor starts on the next four stroke operation.

The operation and valve timing of combustion chamber 27 is identical except that opening 29 in sleeve 25 is located 90° ahead or behind opening 30, depending on whether combustion chamber 27 fires before or after combustion chamber 28.

As previously explained, the reciprocating motion of the sleeve 25 is translated into rotary motion of the gear 19 by the agency of the sliding couple between the cam follower 13 and the rotating member 40.

Although I have herein shown and described my invention in what I have conceived to be the most practical and preferred embodiment, it is recognized that departures may be made therefrom within the scope of my invention, which is not to be limited to the details disclosed herein but is to be accorded the full scope of the claims

so as to embrace any and all equivalent structures.

What I consider to be the essence of my invention in the form illustrated is an internal combustion engine comprising a housing with a longitudinal cylindrical bore through said housing, a reciprocating sleeve disposed in said bore and divided into two compartments by a diaphragm, a compression head disposed within each end of said reciprocating sleeve, a cam follower mounted on one end of said reciprocating sleeve following a stationary cam race defining a simple harmonic curve designed for fourstroke operation, the said cam follower being slidably coupled to one of the said compression heads for translating the reciprocatory motion of the sleeve into a rotary motion.

Power units of the character described may be employed singly, as for example in the manner illustrated in Figure 1, but are adaptable for assembly in various combinations. For example, in in-line engine, with either an odd or even number of power units may be laid horizontally within an airplane wing, or if the installation is otherwise, the power units may be mounted vertically parallel. Or a radial type engine may be assembled by utilizing pinions in place of the gear 19, and a ring gear. These and possibly other adaptations of the invention are matters of design within the range of mechanical skill, as is also the provision for lubrication, carburetion, manifolding, cooling and the like, which are known to the art.

Modifications of the form shown which will nevertheless embody the principles of my invention may include a single combustion chamber instead of the double type illustrated, which would require some form of inertia element such as a flywheel which could occupy the position of gear 19 or be otherwise located in the power takeoff assembly.

Certain features of my invention, such as the power conversion unit, may be employed in connection with steam engines, pumps, compressors and other devices where reciprocating motion must be converted into rotary motion, or vice versa. Thus, for example, the reciprocating member 12 may derive its movement from steam or compressed air, or other power source. Conversely, the rotating member 40 may be the driving element, and the reciprocating member 12 the driven element, in various modified forms of my power conversion assembly.

Having described my invention, what I claim as new and desire to secure by Letters Patent is:

1. An internal combustion engine comprising: a housing having a cylindrical bore, intake, ignition, and exhaust ports in the wall of said housing, a sleeve mounted for reciprocal and rotational movement within the bore of said housing, said sleeve being formed with a diaphragm and having an opening on each side of the diaphragm adapted upon rotation of the sleeve to periodically register with the intake, ignition, and exhaust ports, opposed compression heads within the sleeve and supported against reciprocal motion and cooperating with the diaphragm and sleeve to form opposed combustion chambers, whereby successive explosions in the combustion chambers cause reciprocal movement of the sleeve, means translating such reciprocal movement of said sleeve into simultaneous rotary motion thereof, a coupling with said means for taking off the torque of said means, and a driving

member associated with and for delivering the torque of said cam follower.

2. An internal combustion engine comprising: a housing having a cylindrical bore, intake, ignition, and exhaust ports in the wall of said housing, a sleeve mounted for reciprocal and rotational movement within the bore of said housing, said sleeve being formed with a diaphragm and having an opening on each side of the diaphragm circumferentially spaced approximately 90° from center to center adapted upon rotation of the sleeve to periodically register with the intake, ignition, and exhaust ports, opposed compression heads within the sleeve and supported against reciprocal motion and cooperating with the diaphragm and sleeve to form opposed combustion chambers, whereby successive explosions in the combustion chambers cause reciprocal movement of the sleeve, means translating such reciprocal movement of said sleeve into simultaneous rotary motion thereof, and a coupling with said means for taking off the torque of said means.

3. An internal combustion engine comprising: a housing having a cylindrical bore, intake, ignition, and exhaust ports in the wall of said housing, a sleeve mounted for reciprocal and rotational movement within the bore of said housing, and said sleeve being formed with a diaphragm and having an opening on each side of the diaphragm adapted upon rotation of the sleeve to periodically register with the intake, ignition, and exhaust ports, opposed compression heads within the sleeve and supported against reciprocal motion and cooperating with the diaphragm and sleeve to form opposed combustion chambers whereby successive explosions in the combustion chambers cause reciprocal movement of the sleeve, means for translating such reciprocal movement of said sleeve into simultaneous rotary motion thereof, and a coupling with said means for taking off the torque of said means, said means comprising a stationary cam race formed by complementary cams, and a cam follower operating in said race and coupled with said sleeve.

4. An internal combustion engine comprising: a housing having a cylindrical bore, intake, ignition, and exhaust ports in the wall of said housing, a sleeve mounted for reciprocal and rotational movement within the bore of said housing, said intake and exhaust ports extending substantially the length of the reciprocal stroke of the sleeve, and said sleeve being formed with a diaphragm and having an opening on each side of the diaphragm adapted upon rotation of the sleeve to periodically register with the intake, ignition, and exhaust ports, opposed compression heads within the sleeve and supported against reciprocal motion and cooperating with the diaphragm and sleeve to form opposed combustion chambers, whereby successive explosions in the combustion chambers cause reciprocal movement of the sleeve, means for translating such reciprocal movement of said sleeve into simultaneous rotary motion thereof, and a coupling with said means for taking off the torque of said means, said means comprising a stationary cam race, and a cam follower operating in said race and coupled with said sleeve.

5. An internal combustion engine comprising: a housing having a cylindrical bore, intake, ignition, and exhaust ports in the wall of said housing, a sleeve mounted for reciprocal and rotational movement within the bore of said housing, and said sleeve being formed with a diaphragm

and having an opening on each side of the diaphragm adapted upon rotation of the sleeve to periodically register with the intake, ignition and exhaust ports, opposed compression heads within the sleeve and supported against reciprocal motion and cooperating with the diaphragm and sleeve to form opposed combustion chambers whereby successive explosions in the combustion chambers cause reciprocal movement of the sleeve, means for translating such reciprocal movement of said sleeve into simultaneous rotary motion thereof, said means comprising a stationary cam race formed by circular complementary cams defining two cycles of a simple harmonic curve, a cam follower operating in said race and coupled with said sleeve, and a driving member associated with and delivering the torque of said cam follower.

6. An internal combustion engine comprising: a housing having a cylindrical bore, intake, ignition, and exhaust ports in the wall of said housing, a sleeve mounted for reciprocal and rotational movement within the bore of said housing, said intake and exhaust ports extending substantially the length of the reciprocal stroke of the sleeve, and said sleeve being formed with a diaphragm and having an opening on each side of the diaphragm adapted upon rotation of the sleeve to periodically register with the intake, ignition and exhaust ports, opposed compression heads within the sleeve and supported against reciprocal motion and cooperating with the diaphragm and sleeve to form opposed combustion chambers whereby successive explosions in the combustion chambers cause reciprocal movement of the sleeve, means for translating such reciprocal movement of said sleeve into simultaneous rotary motion thereof, said means comprising a stationary cam race formed by complementary cams, and a cam follower operating in said race and coupled with said sleeve, and a driving member associated with and delivering the torque of said cam follower.

7. An internal combustion engine comprising: a housing having a cylindrical bore, intake, ignition, and exhaust ports in the wall of said housing, a sleeve mounted for reciprocal and rotational movement within the bore of said housing, said intake and exhaust ports extending substantially the length of the reciprocal stroke of the sleeve, and said sleeve being formed with a diaphragm and having an opening on each side of the diaphragm adapted upon rotation of the sleeve to periodically register with the intake, ignition, and exhaust ports, opposed compression heads within the sleeve and supported against reciprocal motion and cooperating with the diaphragm and sleeve to form opposed combustion chambers whereby successive explosions in the combustion chambers cause reciprocal movement of said sleeve, means for translating such reciprocal movement of said sleeve into simultaneous rotary motion thereof, said means comprising a stationary cam race formed by complementary cams defining a simple harmonic curve, and a cam follower operating in said race and coupled with said sleeve, and a driving member associated with and delivering the torque of said cam follower.

8. An internal combustion engine comprising: a housing having a cylindrical bore, intake, ignition, and exhaust ports in the wall of said housing, a sleeve mounted for reciprocal and rotational movement within the bore of said housing, said intake and exhaust ports adapted to com-

municate with the interior of said sleeve throughout substantially the length of the reciprocal stroke of the sleeve, and said sleeve being formed with a diaphragm and having an opening on each side of the diaphragm adapted upon rotation of the sleeve to periodically register with the intake, ignition and exhaust ports, opposed compression heads within the sleeve and supported against reciprocal motion and cooperating with the diaphragm and sleeve to form opposed combustion chambers whereby successive explosions in the combustion chambers cause reciprocal movement of said sleeve, means for translating such reciprocal movement of said sleeve into simultaneous rotary motion thereof, said means comprising a stationary cam race formed by complementary cams defining two cycles of a simple harmonic curve, and a cam follower operating in said race and coupled with said sleeve, and a driving member associated with and delivering the torque of said cam follower.

9. An internal combustion engine comprising: a housing having a cylindrical bore, intake, ignition, and exhaust ports in the wall of said housing, a sleeve mounted for reciprocal and rotational movement within the bore of said housing, said sleeve being formed with a diaphragm and having an opening on each side of the diaphragm adapted upon rotation of the sleeve to periodically register with the intake, ignition and exhaust ports, opposed compression heads within the sleeve and supported against reciprocal motion and cooperating with the diaphragm and sleeve to form opposed combustion chambers whereby successive explosions in the combustion chambers cause reciprocal movement of the sleeve, means translating such reciprocal movement of said sleeve into simultaneous rotary motion thereof comprising a circular stationary cam race, a cam follower operating in said race, and a connection between the sleeve and the cam follower whereby longitudinal movement of said sleeve forces said cam follower to travel in said cam race.

10. An internal combustion engine comprising: a housing having a cylindrical bore, intake, ignition, and exhaust ports in the wall of said housing, a sleeve mounted for reciprocal and rotational movement within the bore of said housing, said sleeve being formed with a diaphragm and having an opening on each side of the diaphragm adapted upon rotation of the sleeve to periodically register with the intake, ignition and exhaust ports, opposed compression heads within the sleeve and supported against reciprocal motion and cooperating with the diaphragm and sleeve to form opposed combustion chambers whereby successive explosions in the combustion chambers cause reciprocal movement of the sleeve, means translating such reciprocal movement of said sleeve into simultaneous rotary motion thereof comprising a circular stationary cam race, a cam follower operating in said race, and a connection between the sleeve and the cam follower whereby longitudinal movement of said sleeve forces said cam follower to travel in said cam race, and a coupling with said means for taking off the torque of said means.

11. An internal combustion engine comprising: a housing having a cylindrical bore, intake, ignition, and exhaust ports in the wall of said housing, a sleeve mounted for reciprocal and rotational movement within the bore of said housing, said sleeve being formed with a diaphragm and having an opening on each side of the diaphragm adapted upon rotation of the sleeve to periodically register

with the intake, ignition and exhaust ports, opposed compression heads within the sleeve and supported against reciprocal motion and cooperating with the diaphragm and sleeve to form opposed combustion chambers whereby successive explosions in the combustion chambers cause reciprocal movement of the sleeve, means translating such reciprocal movement of said sleeve into simultaneous rotary motion thereof comprising a circular stationary cam race, a cam follower operating in said race, and a connection between the sleeve and the cam follower whereby longitudinal movement of said sleeve forces said cam follower to travel in said cam race, and a rotating member coupled to the cam follower for delivering the torque of the cam follower, said rotating member and one of said compression heads being joined.

12. An internal combustion engine comprising: a cylinder having peripherally spaced intake and exhaust ports therein, a sleeve rotatably and reciprocably mounted in said cylinder and having a partition intermediate its extremities and a peripherally spaced port on each side of said partition, axially spaced longitudinally stationary compression heads internally of said sleeve for providing opposed combustion chambers on opposite sides of the partition, ignition means for said chambers, and cam operated means for converting the reciprocal motion of the sleeve into unidirectional rotary motion for application to a rotatable driven element.

13. An internal combustion engine as characterized in claim 12 in which the ports of the sleeve cyclically open to the ports of the cylinder for effecting the intake of a combustible element and the exhaust of the products of combustion in different cycles of operation.

14. An internal combustion engine as characterized in claim 12 including: a unidirectional rotatable driven element, said cam operated means including a coupling between the sleeve and said driven element.

15. An internal combustion engine as characterized in claim 12, in which said intake and exhaust ports are of such form and extent that they may selectively register with the ports of said sleeve substantially throughout the strokes of the sleeve.

16. An internal combustion engine as characterized in claim 12 including: means for injecting a lubricant into said cylinder for lubricating the sleeve and said heads during the operation of the engine.

17. An internal combustion engine as characterized in claim 12, in which the spacing of the ports on the cylinder and on the sleeve are such as to effect an overlapping of said ports, respectively, during certain cycles of operation, for insuring an adequate supply of a combustible element to the combustion chambers and the subsequent scavenging of the products of combustion therefrom.

18. An internal combustion engine comprising: a stationary housing having a cylindrical bore, intake, ignition, and exhaust ports in the wall of said housing, a sleeve mounted for reciprocal and unidirectional rotational movement within the bore of said housing, said sleeve being formed with a diaphragm and having an opening adapted upon rotation of the sleeve to periodically register with the intake, ignition, and exhaust ports, a compression head within the sleeve and supported by the housing and cooperating with the diaphragm and sleeve to form a combustion

chamber whereby explosion in the combustion chamber causes longitudinal movement of the sleeve, means translating such longitudinal movement of said sleeve into simultaneous unidirectional rotary motion thereof, and a driving element coupled with said means for delivering the rotational torque of said means.

19. In an internal combustion: a stationary housing, a combustion operated rotatable reciprocating member in the housing, a relatively axial and stationary cam element operatively connected with the reciprocating member adapted to convert the reciprocating motion into unidirectional rotary motion of the reciprocating member, a driving element having its axis of rotation coincident with the longitudinal axis of the reciprocating member, and a coupling between said reciprocating member and said driving element for communicating continuous and corresponding rotation of the reciprocating member to the driving element.

20. An internal combustion engine comprising: a housing having a cylindrical bore, intake, ignition, and exhaust ports in the wall of said housing, a sleeve mounted for reciprocal and unidirectional rotational movement within the bore of said housing, said sleeve being formed with a diaphragm and having an opening adapted upon rotation of the sleeve to periodically register with the intake, ignition and exhaust ports, a compression head within the sleeve and supported by the housing and cooperating with the diaphragm and sleeve to form a combustion chamber

whereby explosion in the combustion chamber causes longitudinal movement of the sleeve, means translating such longitudinal movement of said sleeve into simultaneous rotary motion thereof, and a driving element coupled with said means for taking off the torque of said means, said means comprising a stationary cam race and a cam follower operating in said race and coupled with said sleeve.

21. An internal combustion engine comprising: a housing having a cylindrical bore, intake, ignition, and exhaust ports in the wall of said housing, a sleeve mounted for reciprocal and rotational movement within the bore of said housing, and said sleeve being formed with a diaphragm and having an opening on each side of the diaphragm adapted upon rotation of the sleeve to periodically register with the intake, ignition, and exhaust ports, opposed compression heads within the sleeve and supported against reciprocal motion and cooperating with the diaphragm to form opposed combustion chambers whereby successive explosions in the combustion chambers cause reciprocal movement of the sleeve, means for translating such reciprocal movement of said sleeve into simultaneous rotary motion thereof, means comprising a stationary cam race, and a cam follower operating in said race and coupled with said sleeve, and a driving member associated with and delivering the torque of said cam follower.

JOSEPH M. CALDWELL.
